UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

TERMINAL FOR BUSHINGS.

Application filed July 29, 1922. Serial No. 578,464.

This invention relates to bushing insulators for transformer casings or other constructions in which a conductor passes thru a portion of the construction from which it is to be electrically insulated, and it has for its object, the provision of construction which permits the removal or installation of the bushing without lowering the oil level in the transformer casing or other similar device, and permits all connections to be made on the outside of the transformer, switch, or other device upon which the bushing is used. Another object is to provide a bushing insulator which shall be of improved construction, efficient in operation, and which shall be convenient to install and replace.

In the drawing:

Fig. 1 is a part elevation and part section, showing one form of the invention.

Fig. 2 is a fragmentary view showing a modified form of a portion of the invention.

Fig. 3 is a view similar to Fig. 1 showing a modification of the invention.

Figs. 4 and 5 are fragmentary sections showing modified forms of connections for the lower end of the terminal rod in Fig. 3.

The improvement includes means for drawing the lead up thru the bushing and holding same in place while the weather cap is being tightened. In order to accomplish the desired result with certainty, it is necessary to provide means for preventing rotation of the center rod and a gasket is also necessary for making an air tight joint.

In the particular form shown in Fig. 1, the conductor 10 running thru the bushing is used to provide the necessary force for holding the weather cap 11 in place, and also for providing force between the upper end 12 of the conductor 10 and the terminal cap 11 to insure good electrical contact. Rotation of the conductor 10 may be prevented by projections or an angular shank 13 on the rod and fitting loosely in a bushing 14 secured in the upper end of the opening 15 in the dielectric member 16. To insure tightness, all that is necessary is to insert a gasket 17 and screw the cap terminal 11 down on rod 10 until the washer 18 is drawn up against the bottom of the bushing. This washer may be an ordinary washer, or it may be in the form of a spring washer so that the contraction and expansion of the conductor 10 with the change in temperature of the transformer will not

effect the tightness of the gasket 17. The washer 18 may be provided with ridges or teeth 19 formed thereon to engage notches in the lower end of the bushing 16 to prevent rotation of the washer. The nut 20 is secured to the rod 10 by pin 21 and engages stops 22 on the washer 18 to hold the rod 10 from rotation. This arrangement may be used in conjunction with the angular portion 13 or either may be used independently of one another.

Where the current is small and a spring washer is used, it is possible to use a conductor 10 of small section so that it will have an appreciable stress per unit area without danger of breaking the conductor or bushing. This is particularly true where a steel conductor may be used or one which has a linear coefficient of expansion more nearly that of the porcelain than where a copper conductor is used. If a conducting member is used which has approximately the same coefficient of expansion as the porcelain, the advantage of the spring washer is not so necessary.

It sometimes happens, however, where a long bushing is used and there is considerable expansion in the conductor owing to an increase in temperature that the expansion in this conductor will reduce the pressure on the gasket and permit a leak. This reduction in the pressure may also permit an increase in the contact resistance between the conductor and the terminal cap. It is seen that by providing the necessary spring in the washer that this difficulty may be overcome and all stresses on the bushing under normal conditions will be in compression.

The length of the bushing frequently varies slightly, and it is advisable to compensate for this change in length. This may be accomplished by adjusting the nut 20 below the washer 18. The nut may be prevented from turning by pinning as by pin 21 or brazing to the rod 10. Where the rod 10, nut 20 and washer 18 are brazed or cemented together, or other means are provided so that they will not rotate with respect to each other, the rib portion 13 of the conductor 10 together with the bushing 14 are not essential to prevent rotation, as the washer may have its projecting ribs 19 engaging corresponding grooves in the lower end of the bushing. It will be seen that with this arrangement, it is possible to prevent rotation and at the same

time provide a spring in the center element so as to insure tightness of the gasket 17 and a good electrical contact between the center conductor and the terminal cap 11 at all times. The lower end of the rod may be made in a variety of ways—another form being shown in Fig. 2.

In Fig. 2 the conductor 23 is provided with an enlarged portion having ribs 24. These ribs engage corresponding recesses in the spring washer 25; the spring washer in turn has projecting ribs 26 which engage corresponding grooves in the insulating member. The arrangement shown provides means for holding the lower end of the conductor 23 so that tension may be applied to same. The construction further provides that this washer or the conducting rod will be prevented from rotation so that the terminal cap 11 may be tightened. With the form shown, the washers at the lower end of the bushing preferably do not make a tight joint. This permits the free expansion of the oil or insulating compound between the conductor 10 and the wall of the bushing. This form of construction also permits the additional insulation of the oil film between the conductor 10 and the walls of the bushing. In order to insure the filling of this space, it is sometimes necessary to allow the air to escape by loosening the terminal cap 11 and then retighten. The screw cap 27 provides means for removing the outside connections so that the terminal cap 11 may be tightened or loosened without interference. Where it is not necessary to provide an air or oil tight joint in the bushing, the gasket 17 may be removed or may consist of material which will simply form a cushion between the porcelain and metal.

The improved form of terminal shown in Fig. 3 provides means for removing or replacing a bushing in a transformer or other device without disturbing any connections other than those at the top of the bushing. Means are also provided for making an air or oil tight joint at the bottom of the bushing. With the improvement as shown, it is not necessary in the tightening operation for the members in contact with the gasket to rotate with respect to the gasket. This permits tightening more easily, and there is not so much danger of breaking the gasket.

In the device shown, the locking flange washer 28 is threaded tightly on to the conductor 29. During installation, the conductor 29 is drawn up thru the bushing by a wire attached to the eye 30 in the upper end of the conductor. The nut 31 is then screwed down far enough so as to hold the conductor 29 from dropping back. A spring washer 32 or a gasket is then placed between the top of the bushing and the weather cap 33. The weather cap 33 is then tightened by screwing down on the thread 34 until the locking wash-

er 28 at the lower end is drawn up tightly against the bushing or against the gasket 35. The center rod 29 is prevented from rotation by the pin 36 locking it to the locking washer 28. The locking washer in turn is prevented from rotation by lugs or projections 37 which engage in corresponding recesses in the bushing. By providing several holes 38 in the rod, it is possible to make adjustment to compensate for different length bushings.

Where an air or oil tight joint is necessary, a tight fit must be insured between the locking washer 28 and the conductor 29 on which it is threaded. This type of terminal has the advantage, that any pressure within will tend to increase the pressure on the joint and keep the same tight.

Figure 4 shows a slightly different form of lower connection. In this instance, rotation is prevented by the tapered angular section of the nut 39 engaging a corresponding recess in the bushing. Rotation between the locking washer and conductor may be prevented by means of a lock nut 40 or by any other suitable means. If a sufficiently tight fit is secured between the locking washers and the conductor, no other locking means is necessary. In Fig. 4 no gasket is shown between the lower end of the bushing and the locking washer. It is evident, however, that a tight joint may be insured by the use of a suitable gasket.

In Figure 5 a slightly different form is shown where the gasket is inside the locking lugs. The locking washer 41 having projecting lugs 42 is formed by upsetting the conductor 43 or by brazing a suitable piece to same. As the gasket 44 may be quite small in this case, a comparatively hard gasket may be used such as a copper or lead gasket or a copper gasket filled with asbestos or any other suitable form.

The portion 45 of the bushing projecting below the flange 41 tends to increase the insulation to ground and also tends to prevent electrical discharge from the flange 41 and projections 42.

This type of terminal is particularly suited to conditions where a rod or tubular conductor is used in the bushing, and also where it is desired to furnish a fixed position for the lead at the lower end. After leaving the bushing the conductor rod may be bent so as to provide clearance for the attached lead as well as support so that it will not become misplaced and cause breakdown below the surface of the oil.

I claim:

1. In combination a dielectric bushing, a conductor extending thru an opening in said bushing, a holding member connected with said conductor at one end of said bushing, a terminal member having threaded connection with said conductor at the opposite end of said bushing, and a spring washer for tak-

ing up longitudinal play between said conductor and bushing said spring washer having means thereon co-operating with said conductor and bushing for preventing rotation of said conductor in said bushing.

2. In combination a dielectric bushing, a conductor rod extending thru said bushing, means connected with said rod for engaging the inner end of said bushing for limiting the

10 outward movement of said rod, means removably connected with the outer end of said rod for holding the end of said rod against movement into said bushing, means for preventing rotation of said rod in said bushing, and a closure member threaded onto said rod at the outer end thereof and having a bearing portion registering with said bushing and exerting an outward tension on said rod.

3. In combination a dielectric bushing, a conductor rod extending thru said bushing, means for limiting outward movement of said rod, a nut threaded on the outer end of said rod, a weather cap threaded on the outer end of said rod independently of said nut, and having a bearing portion registering with said bushing and a spring washer interacting between said conductor rod and bushing so that said weather cap when tightened exerts pressure on said washer.

30 4. In combination a dielectric bushing having an angular shaped opening, a conductor rod extending thru said bushing and having an angular shaped portion disposed in said opening to prevent rotation thereof relative to said bushing, a stop connected with the inner end of said rod for limiting the outward movement thereof, means for holding said rod against retraction into said bushing and an imperforate cap threaded on the outer end of said rod and having a bearing portion registering with said bushing for closing the opening thru said bushing, the threaded connection between said cap and rod exerting outward tension on said rod to press said cap toward said bushing and to insure good electrical contact between said cap and rod.

50 5. In combination a dielectric bushing, a conductor rod extending thru said bushing, a stop at the inner end of said rod for limiting outward movement thereof, a spring washer interposed between said stop and bushing, and means on said washer co-operating with said conductor and bushing for preventing rotation of said rod relative to said bushing.

55 6. In combination a dielectric bushing having an angular shaped opening, a conductor rod extending thru said bushing, a stop on the inner end of said rod for limiting outward movement thereof, a terminal member

threaded on the outer end of said rod, said rod having an angular portion thereon disposed in said opening for holding said rod against rotation when said terminal member is rotated, a spring washer interposed between said stop and said dielectric member and supplementary means on said washer co-operating with said rod and bushing for resisting rotation of said rod.

7. In combination an elongated tubular dielectric bushing having an angular shaped opening, a conductor rod extending thru said bushing and having an angular portion thereon for preventing rotation relative to said bushing, a stop adjustably connected with the inner end of said rod for limiting outward movement thereof, a spring washer interposed between said stop and the inner end of said bushing, a nut threaded on the outer end of said rod for preventing retraction of said rod in said bushing, an imperforate weather cap threaded on the outer end of said rod independently of said nut, and a gasket interposed between said weather cap and the end of said bushing.

8. In combination, a dielectric bushing, a conductor rod extending through said bushing, a stop connected with said rod for limiting the outward movement of said rod, a nut threaded on the outer end of said rod, a weather cap threaded on the outer end of said rod independently of said nut and having a bearing portion registering with said bushing, and a spring washer interacting between said conductor rod and bushing so that said weather cap when tightened exerts pressure on said washer.

9. In combination, a dielectric bushing having an angular shaped opening, a conductor rod extending through said bushing and having an angular shaped portion disposed in said opening to prevent rotation thereof relative to said bushing, a stop connected with the inner end of said rod for limiting the outward movement thereof, a stop removably secured to the outer end of said rod for holding said rod against retraction into said bushing, and an imperforate cap threaded on the outer end of said rod and having a bearing portion registering with said bushing for closing the opening through said bushing, the threaded connection between said cap and rod being arranged to exert outward tension on said rod to press said cap toward said bushing and to insure good electrical contact between said cap and rod.

In testimony whereof I have signed my name to this specification on this 25th day of July, A. D. 1922.

ARTHUR O. AUSTIN.
